UNITED STATES PATENT OFFICE.

JOHN A. MOSHER, OF CHICAGO, ILLINOIS, ASSIGNOR TO THE ADAMS & WESTLAKE COMPANY, OF ILLINOIS.

HASP-FASTENER.

SPECIFICATION forming part of Letters Patent No. 605,645, dated June 14, 1898.

Application filed January 26, 1898. Serial No. 668,089. (No model.)

To all whom it may concern:

Be it known that I, JOHN A. MOSHER, a citizen of the United States of America, and a resident of Chicago, county of Cook, and 5 State of Illinois, have invented certain new and useful Improvements in Hasps, of which the following is a specification.

The invention relates to hasps for securing the covers of boxes, such as camera-cases and 10 the like; and its object is to provide a secure fastening for such a cover, which includes a spring member adapted to be brought to a tension in the act of locking and which automatically locks itself against the strain due 15 to an effort to lift the cover, while it may be easily disengaged without the use of a key.

The invention consists in a shouldered latch-piece secured by means of a link-plate to an elastic attaching-plate adapted to be fixed to 20 the cover of the box, the latch-piece being adapted to enter a socketed plate fixed to the body of the box and to thereby bring the elastic plate to a tension, the pivotal point of attachment to the link being carried beyond the 25 engaging shoulders, so that strain incident to the lifting of the cover of the box tends to draw the latch-piece into the socket.

In the accompanying drawings, Figure 1 is a detail elevation of a box, showing the cover 30 closed and the hasp made fast. Fig. 2 is a detail sectional view on the line 2 2 of Fig. 1. Fig. 3 is a rear or inside elevation of the hasp removed from the box. Fig. 4 is a detail plan view of the box-cover with the latch-piece of the hasp extended and in the position it assumes as it is about to engage the socket-plate. Fig. 5 is a plan view of the attaching-plate and the latch-piece, the latter being 35 fully extended. Fig. 6 shows a plan view 40 and an elevation of the socket-plate removed from the body of the box. Fig. 7 is a detail sectional view on the line 7 7 of Fig. 1, and Fig. 8 is a detail sectional view on the line 8 8 of Fig. 1.

45 A portion of the body of the box is shown at A, and a portion of the box-cover at B. The attaching-plate of the hasp is shown at C and is secured to the cover of the box by means of nails or screws, as c. The socket- 50 plate for receiving the latch-piece of the hasp

is shown at D and is intended to be secured to the body of the box by nails or screws, as d.

The latch-piece E of the hasp is attached to the plate C by means of a link-plate F, the outer end of the plate C being curved downwardly and inwardly to secure a pintle C', upon which the link-plate F swings.

The latch-piece E is oblong in its general contour and has at each side a downwardly or inwardly projecting flange or wing e, between which is fixed the pintle f, by means of which the latch-piece E is secured to the link-plate F, this pintle being located back of or below the plane of the body portion of the latch-piece. The heel of the latch-piece 65 E extends backwardly beyond the pintle f and is bifurcated or apertured to accommodate the link-plate F, so that the latch-piece may be thrown backwardly beyond the plane of the latter, as plainly shown by the dotted 70 lines in Fig. 7. The two end pieces of the heel of the latch-piece are shouldered, as indicated at g.

The recess of the socket-plate D has a general conformation of and is adapted to receive 75 the latch-piece E and is prolonged upwardly through the end of the plate D, as shown at H, to receive the link-plate F. The link-plate F being of less depth than the body portion 80 of the latch-piece E, the recess H is of less depth than that portion of the recess adapted to receive the latch-piece, thereby forming a pair of shoulders at the upper end of this recess, as shown at h h, and these shoulders project downwardly over the major portion 85 of the recess.

In securing the hasp the body portion of the latch-piece E is thrown backwardly to the position shown by dotted lines in Fig. 7 and the shoulders g g are engaged with the shoulders h h. The outer end of the latch-piece E is now thrown backwardly, so that the latch-piece and the link-plate F enter the recess of the socket-plate D. As the pintle f passes beyond the plane of the surface of the 95 socket-plate, and consequently beyond the shoulders h h, strain incident to an effort to open the cover of the box tends to draw the latch-piece farther into the recess of the socket-plate.

The attaching nails or screws *c* are preferably located at the inner end of the attaching-plate *C*. The outer end of each normally rises slightly from the surface of the box-cover, and its attaching-plate is, when this form of construction is followed, of spring metal. The strain incident to the throwing of the latch-piece *E* into the recess of the socket-plate draws the outer end of the plate *C* downwardly, and the elasticity of the latter therefore maintains a constant strain upon the latch-piece, thereby preventing it from rattling loose. This construction is of advantage also in that the elasticity of the plate *C* will take up the wear of the shoulders *g h*.

The recess of the socket-plate *D* may be extended downwardly, so that it will be a little longer than the latch-piece *E*, so that the user may insert his thumb-nail under the end of the latter for the purpose of disengaging the hasp.

I claim as my invention—

1. In a hasp the combination with a socket-plate, and a latch-piece adapted to hook into the recess of the socket-plate, of an attaching-plate having a spring-shank, and a link connecting the latch-piece with the attaching-plate.

2. In a hasp, the combination with a hinge-plate having a spring-shank, and a socket-plate having overhanging shoulders at its upper end, of a latch-piece adapted to be caught under the shoulders of the socket-plate and a link for uniting the latch-piece with the shank.

3. The combination with a socket-plate having an overhanging forwardly-projecting shoulder, and a hinge-plate adapted to be secured in a plane perpendicular to the plane of the socket-plate and having an elastic shank normally curved outwardly from its plane of attachment, of a latch-piece adapted to enter the socket-plate and being constructed to engage the shoulder thereof, and a link pivotally attached to the outer end of the hinge-plate and to the latch-piece intermediate of its ends, the pivots of the link being both within the plane of the shoulders of the socket-plate when the parts are in engagement, substantially as described and for the purpose specified.

JOHN A. MOSIHER.
